H. J. SAYERS, OF SALINA, PENNSYLVANIA.

Letters Patent No. 88,744, dated April 6, 1869.

STOVE-PIPE DAMPER.

The Schedule referred to in these Letters Patent and making part of the same.

To all whom it may concern:

Be it known that I, H. J. SAYERS, of Salina, in the county of Venango, and State of Pennsylvania, have invented a new and valuable Improvement in Stove-Dampers; and I do hereby declare that the following is a full, clear, and exact description of the construction and operation of the same, reference being had to the annexed drawings, making a part of this specification, and to the letters and figures of reference marked thereon.

Figure 1, of the drawings, is a side view of my device, and

Figure 2 is a sectional view thereof.

My invention relates to that class of devices by which the draught of a stove, or other similar heating-apparatus, may be increased or diminished at will, and the object is to provide more simple and efficient means for that purpose than have heretofore been devised.

The letter A, of the drawings, represents the ordinary joint of stove-pipe leading from the stove, constructed with an opening therein on the lower side, marked C. This joint of stove-pipe has raised shoulders, as shown at d, which serve not only to hold the next joint attached thereto in its proper place, but also as guides and supports for the sleeve H, next mentioned.

The letter H represents a sleeve of sheet-iron of sufficient length, to fit closely between the shoulders e of the stove-pipe, and of sufficient diameter to fit closely around the stove-pipe, and yet move thereon with ease.

I also make an opening in one side of this sleeve, corresponding in all respects with the opening O of the stove-pipe.

On the side of this sleeve, opposite the opening thereon, I affix a handle, marked h, by means of which the sleeve is moved around the stove-pipe at the will of the operator.

My damper is operated as follows, namely:

To lessen the draught of the stove, I adjust the open-

ing in the sleeve immediately over the opening in the stove-pipe, so as to admit air into said openings; the size of the opening thus formed corresponding with the amount of air designed to be admitted.

It will readily be perceived that by these means the draught of the stove is, to a great extent, subject to the will of the operator, inasmuch as the same is dependent upon the size of the opening thus formed or allowed.

I am aware that dampers have been constructed upon the principle of admitting air into the annular flange of the stove below the stove-pipe, but even in that case it is accomplished through a series of small openings extending around the flange, which must all be operated simultaneously, and hence the draught is forced to the centre of the stove-pipe instead of the side, as in my invention.

By forcing the heated air to the centre of the stove-pipe, a great part of the heat thereof passes to the chimney, and is lost, while by my device the heated air is forced against the side of the stove-pipe, and from thence to the apartment.

I do not claim, broadly, the introduction of cold air to the heated air after the same has left the stove, for, as I have observed, that device is not new; but

What I do claim as my invention, and desire to secure by Letters Patent, is—

The combination of the sleeve H, with its handle h and aperture, as described, with a stove-pipe having flanches d and aperture C, arranged in such manner that the flanches of the stove-pipe shall form guides to regulate the movements of said sleeve in the manner and for the purposes herein specified.

In testimony that I claim the above, I have hereunto subscribed my name in the presence of two witnesses.

H. J. SAYERS.
